UNITED STATES PATENT OFFICE

STEPHEN J. VELTON, OF HOUSTON, TEXAS

INTERNAL COMBUSTION ENGINE

Application filed August 11, 1930. Serial No. 474,510.

This invention relates to certain new and useful improvements in internal combustion engines and has more particular reference to an internal combustion engine equipped 5 with eight cylinders.

A primary object of the invention is, therefore to provide an eight cylinder internal combustion engine, wherein the pistons operable in the cylinders are arranged in pairs 10 and the cylinders of the respective pairs operate simultaneously during their suction and power strokes.

With the above and numerous other objects in view, as will be apparent as the description proceeds, the invention consists in 15 the novel combination and arrangement and construction of parts hereinafter described in detail, shown in the accompanying drawings, and claimed.

20 In the drawings:

Figure 1 is a top plan view of the improved internal combustion engine.

Figure 2 is a vertical longitudinal sectional view therethrough.

25 Figure 3 is a vertical transverse sectional view therethrough.

Figure 4 is a plan view of one section of a sectional clamping arm.

Figure 5 is a fragmentary detail view, 30 partly in section and partly in elevation, for more clearly illustrating the application of the sectional clamping arm.

With reference more in detail, to the drawings, it will be seen that the internal 35 combustion engine designated generally by the reference character E comprises a suitable cylinder block 1, crank case 2, and cylinder head 3. The cylinder head is suitably focused onto the block 1 as at 4.

40 Arranged in the cylinder block 1 is a plurality of cylinders 5 and 6 arranged on opposite sides of the cylinder block and the cylinders 5 and 6 are arranged in pairs, there being one cylinder 5 and one cylinder 6 to each pair of cylinders.

There are four of such pairs of cylinders 5 and 6, thus providing eight cylinders for the internal combustion engine. The cylinder head C is provided with a plurality of longitudinally spaced internal recesses or com-

bustion chambers 7, there being four of said combustion chambers 7, there being one combustion chamber 7 common to a pair of cylinders 5 and 6.

Arranged on opposite sides of each combustion chamber 7 are spark plugs 8 and 9, there being one spark plug 8 for each cylinder 5 and one spark plug 9 for each cylinder 6.

Mounted for reciprocation in the cylinders 5 and 6 are pistons 10 and 11 and each of the pistons includes a piston rod 12, provided at each lower end with an enlarged head 13.

A two-part clamp designated generally by 65 the reference character 14, connects the head 13 of a pair of piston rods 12. Said clamp 14 comprises a pair of complementary sections 15, that are clamped together at their ends through the medium of suitable bolt and 70 nut fastening elements 16. Each of the parts 15 inwardly thereof is provided with a recess 17 for accommodating a portion of a head 13, and a vertically disposed semi-cylindrical bore 18, leads upwardly from the recess 17 75 for accommodating a portion of the piston rods 12. Thus, it will be apparent that when the parts or sections 15 of the clamping rods 14 are in assembled relation, the pockets 17 mate for accommodating the head 13 of the 80 piston rod 12 to be connected together, while the bores 18 mate for accommodating the rods 12.

The clamping rods 14 extend transversely 85 of the cylinder block, below the cylinders 5 and 6 and are adapted for vertical reciprocatory movement in said cylinder block.

Each of the sections 15 of the clamping members 14 intermediate the ends thereof has depending from the lower edge thereof a 90 semi-circular or arcuate apertured portion 19, and these apertured portions 19 sit within the upper forked end of a link 20, which end of the link is pivotally connected through the portion 19 through the medium of a suitable 95 bolt 21.

The links 20 connect the coupling members 14 with the cranks 22 of a crank shaft 23, journaled in the crank case 2. The crank shaft 23 adjacent its rearward end and inter- 100

iorly of the crank case is provided with a suitable fly wheel 24. The fly wheel 24 will, of course, provide the necessary balance, during the operation of the internal combustion 5 engine.

On one side thereof, the cylinder block 1 and cylinder head 3 are suitably formed to cooperate in providing a plurality of pairs of intake ports 25, there being one pair of ports.

10 for each of said pairs of cylinders 5 and 6 and each pair of ports 25 including one intake port for the cylinder 5 and one intake port for the cylinder 6 of the respective pairs of ports.

Likewise, on the opposite side thereof, said 15 cylinder block and cylinder head are provided to cooperate in forming exhaust ports 26, the exhaust ports being also arranged in pairs, there being one pair of said exhaust ports for the pair of cylinders 5 and 6, as is apparent.

20 Suitably bolted to the cylinder block and cylinder head as at 27 and 28 is an intake manifold, which includes pairs of vertically disposed piston valves 29, there being one piston valve 29 for each of the intake ports 25.

25 The piston valves 29 control passage of fluid from a common intake manifold pipe 30 into the cylinders 5 and 6 through the passages 25. Each of the piston valves 29 includes a vertically disposed cylinder, having 30 ports registering with the intake pipe 30 and the ports 25, and controlling the ports of the cylinder is a piston 31, mounted for reciprocation within the cylinder. Each of the pistons 31 include a piston rod 32, that slidably 35 extends through the lower ends of said cylinder.

At said lower ends, each of the piston rods 32 is provided with a suitable head for riding over the peripheral surface of cams 33, 40 mounted on a horizontal cam shaft 34, supported horizontally and laterally with respect to the cylinder block through the medium of suitable brackets 35 that extend outwardly from the side of the cylinder block.

45 The exhaust manifold structure on the opposite side of the cylinder block and head is substantially the same as the intake manifold structure, and said exhaust manifold structure comprises a plurality of pairs of 50 exhaust valves 36, each including a cylinder 37, the cylinders 37 of the valves 36 communicating with a common exhaust pipe 38. Arranged in the cylinders 36 for controlling the passage of the exhaust gases from the 55 port 26, through the cylinders and into the exhaust pipe 38 are reciprocably mounted pistons 39, that at piston rods 40 extending slidably through the lower ends of the cylinders. The lower ends of the piston rods 40 are provided with suitable heads ridable over the cams 33' mounted on a suitable cam shaft 34' horizontally supported laterally with respect to the adjacent sides of the cylinder block through the medium of the 60 brackets 35'.

For maintaining at all times the heads of the piston rods 32, and 40 in engagement with the cams 33 and 33' there is convoluted about each of the piston rods a suitable coil spring 41, that at its upper end bears against 70 the lower end of the adjacent cylinder, and at its lower end bears against a suitable collar 42 formed on the respective piston rods.

Any suitable source of power (not shown) is utilized for rotating the cam shafts 34, 75 34' in suitable timed relation with respect to one another and with respect to the pistons 10 and 11.

It is apparent that an internal combustion engine of this character operates on the four-cycle system, and that each pair of pistons 10 and 11 operate simultaneously with respect to one another and that the respective pairs of pistons operate in suitable timed relation relative to one another, so that instead of the usual four-cylinder type of engine, there is but one piston firing, and there is according to the present invention, two pistons firing at the same time. However, it is to be noted that in the present invention, for each piston, 80 there is provided a separate and distinct spark plug, and that the spark plugs being arranged in pairs will ignite the fluid compressed in the compression chamber 7, upon the upstroke of a pair of pistons 10 and 11. 85

The principal effect of this arrangement is in the provision of a more powerful engine, productive of maximum power with a minimum amount of wear.

What is claimed is:

1. An internal combustion engine comprising, in combination, a plurality of cylinders, pistons operable in the cylinders, a crank shaft, means operatively connecting said pistons in pairs to the cranks of said crank shaft, a combustion chamber common to the cylinders of the respective pairs of pistons, and a pair of spark plugs arranged one to each side of each of said combustion chambers, an intake manifold, a pair of inlet ports connecting the cylinders of the respective pairs with said intake manifold, an exhaust manifold, a pair of exhaust passages connecting the cylinders of the respective pairs of cylinders with said exhaust manifold, and valve means for controlling said intake passages and said exhaust passages respectively.

2. An internal combustion engine comprising in combination a cylinder block, a plurality of cylinders arranged in said cylinder block, pistons operable in said cylinders, said pistons being arranged in pairs, a crank shaft, means operatively connecting the pistons of the respective pairs of pistons to the cranks of the crank shaft, whereby the pistons of the respective pairs are actuated simultaneously, a combustion chamber common to each pair of cylinders, a pair of spark plugs arranged one to each side of each of the combustion chambers, there being one spark plug for each 100

of said pistons, intake ports on one side of said block, said intake ports being arranged in pairs, there being one pair of intake ports for each pair of cylinders, exhaust ports arranged in the opposite side of said blocks said exhaust ports being arranged in pairs, there being one pair of exhaust ports for each pair of cylinders.

3. An internal combustion engine comprising in combination a cylinder block, a plurality of cylinders arranged in said cylinder block, pistons operable in said cylinders, said pistons being arranged in pairs, a crank shaft, means operatively connecting the pistons of the respective pairs of pistons to the cranks of the crank shaft, whereby the pistons of the respective pairs are actuated simultaneously, a combustion chamber common to each pair of cylinders, a pair of spark plugs arranged one to each side of each of the combustion chambers, there being one spark plug for each of said pistons, intake ports on one side of said block, said intake ports being arranged in pairs, there being one pair of intake ports for each pair of cylinders, exhaust ports arranged on the opposite side of said block, said exhaust ports being arranged in pairs, there being one pair of exhaust ports for each pair of cylinders, an intake manifold common to said intake ports, an exhaust manifold common to said ports, each of said exhaust manifolds including a plurality of valves, there being one valve for each of the ports.

4. An internal combustion engine comprising in combination, a plurality of cylinders, pistons operable in said cylinders, said pistons being arranged in pairs, a crank shaft, means operatively connecting the pistons of the respective pairs of pistons to the cranks of the crank shaft, whereby the pistons of the respective pairs are actuated simultaneously, a combustion chamber common to each pair of cylinders, a pair of spark plugs for each of the combustion chambers, intake ports on one side of said engine, said intake ports being arranged in pairs, there being one pair of intake ports for each pair of cylinders, exhaust ports arranged in the opposite side of said engine, said exhaust ports being arranged in pairs, there being one pair of exhaust ports for each pair of cylinders, an intake manifold common to said intake ports, an exhaust manifold common to said ports, each of said exhaust manifolds including a plurality of valves, there being one valve for each of the ports, brackets on from opposite sides of said engine, a cam shaft supported on the brackets one to each side of said engine, each of said cam shafts provided with a plurality of cams, there being one cam for each of said valves, and the valves of said intake and exhaust manifold respectively provided with a spring pressed piston valve rod for engagement with a cam, the valve rods of the valves of said intake manifold engaging the cams

on one of said cam shafts, and the valve rod of the valves of the exhaust manifold engaging the cams on the other of said shafts.

5. An internal combustion engine comprising in combination, a plurality of cylinders, pistons operable in the cylinders, said pistons being arranged in pairs, means for operatively connecting each pair of pistons with a crank of the crank shaft for simultaneously operating the pistons of the respective pairs, a combustion chamber common to the cylinders of the respective pairs, a valve controlled intake manifold on one side of said internal combustion engine, and including a plurality of intake passages, said passages being arranged in pairs, and there being one pair of passages for each pair of cylinders, an exhaust manifold on the opposite side of the internal combustion engine, and including a plurality of pairs of exhaust passages, there being one pair of exhaust passages for each pair of cylinders, and means for igniting the fuel in the respective combustion chambers when the pistons of the respective pairs of pistons complete their compression stroke.

6. An internal combustion engine comprising in combination, a plurality of cylinders, pistons operable in the cylinders, said pistons being arranged in pairs, means for operatively connecting each pair of pistons with a crank of the crank shaft for simultaneously operating the pistons of the respective pairs, a combustion chamber common to the cylinders of the respective pairs, a valve controlled intake manifold on one side of said internal combustion engine, and including a plurality of intake passages, said passages being arranged in pairs, and there being one pair of passages for each pair of cylinders, an exhaust manifold on the opposite side of the internal combustion engine, and including a plurality of pairs of exhaust passages, there being one pair of exhaust passages for each pair of cylinders, and means for igniting the fuel in the respective compression chambers when the pistons of the respective pairs of pistons complete their compression stroke, and cam controlled valves for controlling the respective passages of said intake and exhaust manifolds respectively.

In testimony whereof I affix my signature.
STEPHEN J. VELTON.
